CLAIM

I claim the ornamental design for a sample collection device, as shown and described.

DESCRIPTION

FIG. 1 is a perspective view of a sample collection device embodying the design, with the device in a closed position. FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof; and,

FIG. 8 is a perspective view of the device in an open position.

The broken lines in the drawings depict portions of the sample collection device that form no part of the claimed design.
